GAS VALVE

Edward E. Hayden, Visalia, Calif., assignor to
California Wire Products Co., Inc., Visalia,
Calif., a corporation of California

Application September 20, 1949; Serial No. 116,817

4 Claims. (Cl. 137—627.5)

1

This invention relates to valves, and more particularly to a valve especially adapted to control the flow of gas from one receptacle to another.

An object of the invention is to provide a simple and compact valve mechanism which will provide for passage of gas in a direction controlled by the will of the operator.

Another object of the invention is to provide a valve mechanism that is adapted to be easily and quickly operated, the valves of which are capable of closing tightly so as to control the flow of gas from one receptacle to another.

Another object of the invention is to provide a valve mechanism which, when actuated, will permit gas to pass from one receptacle to another and which, when at rest, will permit a passageway from one of the receptacles permitting gas to be exhausted into the outside atmosphere.

Other objects reside in the provision of a strong, durable and efficient valve mechanism which is simple in construction and relatively inexpensive to manufacture.

These, together with the various ancillary objects of the invention which will become apparent as the following description proceeds, are attained by this valve mechanism, a preferred embodiment of which has been illustrated in the accompanying drawings, wherein:

Figure 1 is a side elevational view of the valve mechanism comprising the present invention;

Figure 2 is a top plan view of the valve mechanism shown in Figure 1;

Figure 3 is a vertical sectional view of the valve mechanism shown in Figure 1, in an enlarged scale for greater detail; and

Figure 4 is a vertical sectional view as taken along line 4—4 in Figure 3.

With continued reference to the accompanying drawings wherein like reference numerals designate similar parts throughout the various views, 10 generally represents a casing of a desired shape in which the major portion of the elements of the valve mechanism are emplaced. Extending through one of the side walls of the casing 10 is a cylinder 12 which is in alignment with a bore 14 extending through the rest of the casing and being enlarged as at 15. A plunger 16 having a tubular portion 18 is inserted in the cylinder 12. The tubular portion 18 has a plurality of 45 annularly spaced apertures such as 20 therein which are adapted to selectively communicate with the atmosphere at the outer end of the cylinder 12. A pair of oppositely disposed slots 22 are formed in the tubular portion 18 of the 50

2

plunger 16 and a pin 24 is secured to the inner walls of the cylinder 12 and extends through the slot to limit the outward movement of the plunger 16.

A spring 26 is positioned in the cylinder 12 and biases the plunger 16 outwardly and the inner end wall 28 of the cylinder 12 inwardly. The cylinder 12 has a recess 30 therein together with a plurality of spaced apertures 32 extending through its side walls in communication with the recess 30. The cylinder 12 is secured to a disk 34 which is urged by spring 36 to seat upon a valve seat 38 secured to the shoulder 40 formed by the difference in diameter of the bores 14 and 15. The annular ring 38 is formed from a flexible and compressible material such as rubber and forms an air-tight seal when used in conjunction with the disk 34. Secured to the disk 34 and extending therefrom is a tubular member 42 which is slidably inserted into a recess 44 in the plug 46 which is threadedly engaged, as at 48, in the side wall adjacent the bore 15 of the casing. The opposed ends of the spring 36 bias the disk 34 and the plug 46. A compressible washer 50 is inserted between the plug and the casing. In communication with the bore 15 is a bore 52 which is internally threaded, as at 54, for reception of means to supply gas under pressure. In communication with the bore 14 is a passage or bore 56 which extends through the externally threaded base 58 of the casing.

As best shown in Figure 3, a cylinder 60 is secured in threaded engagement with the base 58 of the casing and has a piston 62 therein.

Pivoted by means of a suitable pin 64 to the casing 10 is a valve trigger 66 which additionally is pivotally connected by pin 68 to the plunger 16. A suitable handle 70 is secured to the lever portion of the trigger mechanism 66. As best shown in Figures 1 and 2, the lever portion of the trigger mechanism 66 is inserted in a suitable slot in the head of the plunger 16.

In operation, the initial movement of the valve trigger 66 inwardly causes the escape ports 20 to be closed while depressing spring 26. The outward travel of the plunger 16, however, is limited by the retaining pin 24 in the slot 22. Farther inward movement of the trigger 66 will effect movement of the cylinder 12 by engagement of the shoulder on the plunger with the cylinder, thereby causing the solid cylindrical portion 28 of the cylinder 12 to lift the disk 34 off the valve seat 38 and to compress spring 36. Gas entering through bore 52 is allowed to pass out of passage 56. Releasing of the trigger 66

first closes the valve comprising the disk 34 and the seat 38, preventing further passage of gas out of the passage 56. The further release of the control trigger 66 allows outer escape port formed by the apertures 20 and 14 to open. Air may now return inward through passage 56 entering inner escape port 32 and passing through the hollow section 30 of the cylinder 12 and through the hollow section 18 of the plunger to exhaust through the outer escape port formed by the 10 apertures 14 and 20. The assembly of the various parts of the valve mechanism is possible because the valve plug 46 is detachably secured to the casing. The valve plug also acts as a bearing through which the valve comprising the disk 34 and the cylinder 42 may slide.

It is not intended to limit the use of this valve to any particular device, and many various uses may be found for this invention. Since, from the foregoing, the construction and advantages of 20 this valve mechanism are readily apparent, further description is believed to be unnecessary.

However, since numerous modifications will occur to those skilled in the art after a consideration of the specification and the accompanying drawings, it is not intended to limit the invention to the precise embodiment shown and described, but all suitable modifications may be resorted to which fall within the scope of the appended claims.

Having described the invention, what is claimed as new is:

1. A valve mechanism comprising a casing having a longitudinal bore therethrough and a pair of first and second longitudinally offset transverse bores opening perpendicularly into the side wall of said longitudinal bore at diametrically opposite points therealong, said casing having a counterbore in one end thereof in alignment with said longitudinal bore and forming an annular shoulder between said transverse bores, a plug closing said one end of said casing, a valve actuator pivoted to said casing overlying the other end of said casing and swingable about an axis perpendicular to the axes of said transverse bores, valve means disposed within said longitudinal bore and operated by said actuator to selectively communicate said transverse bores with one another, said valve means including a spring urged valve seating against said offset shoulder, a sleeve valve pivotally secured to said valve actuator and being slidably disposed in said longitudinal bore at the other end of said casing and a resilient spring interposed between said valves, said sleeve valve having exhaust ports therein adjacent its pivotal connection to said actuator, said exhaust ports being closed when said spring urged valve is open.

2. A valve mechanism comprising a cylindrical casing having a longitudinal bore therethrough and a pair of first and second longitudinally offset parallel transverse bores opening into the side wall of said casing at diametrically opposite points therealong, said casing having a counterbore opening into one end thereof and forming an annular shoulder within said casing between said transverse bores, a plug closing said one end of said casing, a tube mounted in said longitudinal bore at the other end of said casing, pin means projecting radially inwardly from said tube, a sleeve valve slidably disposed in said tube and having a longitudinal slot engaged by said pin means to limit sliding movement of the sleeve, a valve actuator connected to said sleeve valve and said casing for sliding the sleeve valve in the 75

tube, said sleeve valve having exhaust ports therein adjacent its connection to said actuator, said exhaust ports being movable into and out of said tube upon movement of said actuator, a second valve, said second valve seating against said annular shoulder and means interconnecting said second valve and said sleeve valve whereby movement of the sleeve valve into the tube unseats the second valve to afford free passage between said transverse bores.

3. A valve mechanism comprising a casing having a longitudinal bore therethrough and a pair of first and second longitudinally offset transverse bores opening perpendicularly into the side wall of said longitudinal bore at diametrically opposite points therealong, said casing having a counterbore in one end thereof in alignment with said longitudinal bore and forming an annular shoulder between said transverse bores, a plug closing said one end of said casing, a valve actuator pivoted to said casing overlying the other end of said casing and swingable about an axis perpendicular to the axes of said transverse bores, valve means disposed within said longitudinal bore and operated by said actuator to selectively communicate said transverse bores with one another, said valve means including a spring urged valve seating against said offset shoulder, a sleeve valve pivotally secured to said valve actuator and being slidably disposed in said longitudinal bores at the other end of said casing and a resilient spring interposed between said valve, said sleeve valve having exhaust ports therein adjacent its pivotal connection to said actuator, said exhaust ports being closed when said spring urged valve is open, said plug having a blind bore therein, a tubular extension on said spring urged valve slidably extending into said blind bore, and a spring in said extension seating in said blind bore urging said valve into seating engagement with said shoulder.

4. A valve mechanism comprising a cylindrical casing having communicating first and second aligned valve chambers therein and first and second transverse bores opening into said chambers, said transverse bores being in longitudinally offset alignment with one another, said first chamber opening into one end of said casing, an annular shoulder in said casing between said chambers constituting a valve seat, a valve seated on said shoulder, an actuating lever pivoted to said one end of said casing about an axis perpendicular to said transverse bores, a sleeve valve connected to said actuator and disposed within the end opening of said first chamber, and means interconnecting said first mentioned valve and said sleeve valve whereby movement of said actuator sequentially opens and closes said valves.
